Attorney.

UNITED STATES PATENT OFFICE.

ALBERT H. EDDY, OF CRANSTON, RHODE ISLAND, ASSIGNOR TO PAYTON & KELLY CO., OF PROVIDENCE, RHODE ISLAND, A CORPORATION OF RHODE ISLAND.

BELT BUCKLE.

1,406,449.

Specification of Letters Patent. Patented Feb. 14, 1922.

Application filed April 28, 1920. Serial No. 377,200.

To all whom it may concern:

Be it known that I, ALBERT H. EDDY, a citizen of the United States, and resident of Pawtuxet, city of Cranston, in the county 5 of Providence and State of Rhode Island, have invented certain new and useful Improvements in Belt Buckles, of which the following is a specification.

This invention relates to belt buckles of 10 the class adapted to automatically grip and bind belts in adjusted position about the body of the wearer, and the object of this invention is to provide a simple and practical buckle of this character which is very 15 strong and durable in construction and which may be formed complete without the use of solder.

The nature and advantages of the invention will be better understood when the following 20 detail description is taken in connection with the accompanying drawings, the invention residing in the combination and arrangement of parts as claimed.

In the drawings forming part of this 25 specification, like numerals of reference indicate similar parts in the several views and wherein:—

Figure 1 is a sectional side elevation illustrating the general construction of my im- 30 proved buckle and arrangement of applying it to a belt.

Figure 2 is a cross sectional end elevation of the body portion of the buckle, showing the rolled edges thereof.

Figure 3 is a perspective view showing the clamp-supporting cross-bar detached.

Figure 4 is a perspective view showing the under side of the clamping member.

Figure 5 is a section on line 5—5 of Figure 1, through the pivoting point of the 40 cross-bar.

Figure 6 is a perspective view showing the under side of my improved buckle.

With reference to the drawings, 10 designates the body portion of the buckle, which 45 may be formed of any suitable material but which is usually formed of thin precious metal, and is provided with rearwardly-turned, oppositely-disposed side walls 11, 50 the edges 12 of which walls are rolled over inwardly, as best illustrated in Figure 2.

In some cases where the stock is made very thin it is also desirable to roll inwardly the ends of the body portion, as

at 13, to further assist in stiffening the 55 stock.

In order to support the usual clamping member, I have provided a cross-bar 14 which it is found to be of great advantage from a practical standpoint, to connect the 60 side walls without the use of solder. Therefore to accomplish this in a simple and practical way, I have turned the ends 15 of this cross-bar upwardly providing hook-shaped portions which are adapted to slide 65 longitudinally into the first loosely-rolled edges 12 of the side walls.

After this bar has been so positioned with its end in engagement with said rolled edge, it is only necessary to swage these rolled 70 edges tightly onto the turned ends of the bar to grip and bind and so secure the bar in the desired position.

In order to provide simple and effective means for pivotally supporting the clamp 75 member in this bar, I have cut away a portion of the rear edge of this bar at 16 and have turned upwardly the ends of this cut-away portion to provide pivoting ears 17 which are pierced at 18 for the reception 80 of the pivoting pin 19 on which the clamp member 20 swings.

This clamp member is preferably cut from sheet stock which is considerably heavier than that of the body portion and is shaped 85 at one end to form a loop or eye-portion 21 to receive one end 22 of the belt, the opposite or gripping end 23 of this clamp being turned back or downwardly at substantially a right angle to the plane of the 90 eye-portion, and the side edges of this clamp being also turned back forming pivoting ears 24 which are pierced at 25 to receive the pivot pin 19.

When this clamp member is mounted to 95 swing in its cross-bar, a tension on the end 22 of the belt causes its edge 23 to grip and bind the opposite ends 26 of the belt against the inner surface of the body portion of the belt buckle, to securely hold the belt in adjusted position about the body of the wearer.

This gripping lip 22 is also adapted when swung up to engage the under side of this cross-bar 15 to also perform the function of limiting the releasing movement of the 100 clamp.

In some instances in addition to inserting the clamp supporting cross-bar 24, I also

provide a second cross bar 27 which may be secured in the same manner as the said clamp cross bar, by clinching its ends under the rolled-over edges of the body side walls.

A buckle of my improved construction is extremely strong and durable, is practical in its operation and may be constructed entirely without the use of solder.

10 I claim:

1. A belt buckle comprising a body having rearwardly turned side walls, each being provided with a rolled-over edge, a cross-bar spaced above said body and having its ends folded to engage and be secured by said roll of said edges, and a belt-gripping member mounted on said bar and having a portion forming a bail to which one end of the belt is attached and having a gripping edge to bind the other portion of the belt against the inner wall of the buckle body.

2. A belt buckle comprising a body having rearwardly turned side walls, a cross-

bar secured to said walls and provided with 25 pivot ears, and an angular belt-clamping member pivoted to said ears on said bar, the handle portion of said clamp forming a bail to receive one end of the belt, the gripping edge of said clamp being adapted 30 to grip and bind another portion of the belt against the back of the body.

3. A belt buckle comprising a body having rearwardly turned side walls, a cross-bar secured to said walls, an angular belt- 35 clamping member pivoted to said bar, the handle portion of said clamp forming a bail to receive one end of the belt, the gripping edge of said clamp being adapted to grip and bind another portion of the belt against 40 the back of the body, said gripping edge being adapted to also engage the under side of said bar to limit the releasing movement of said clamp.

In testimony whereof I affix my signature.

ALBERT H. EDDY.
